Primary Examiner — Sandra Morris(74) *Attorney, Agent, or Firm* — Morgan, Lewis & Bockius LLP(57) **CLAIM**

The ornamental design for a clothes management apparatus, as shown and described.

DESCRIPTION

FIG. 1 is a perspective view of a clothes management apparatus showing our new design;

FIG. 2 is a front view thereof;

FIG. 3 is a rear view thereof;

FIG. 4 is a left side view thereof where the right side view is a mirror image; and,

FIG. 5 is a top plan view thereof where the bottom plan view is a mirror image.

The broken lines are for illustrative purposes only and form no part of the claimed design.
